UNITED STATES PATENT OFFICE.

WILLIAM J. LUTTON, OF PATERSON, NEW JERSEY.

PATTERN MECHANISM FOR LOOMS.

SPECIFICATION forming part of Letters Patent No. 729,880, dated June 2, 1903.

Application filed October 24, 1902. Serial No. 128,521. (No model.)

To all whom it may concern:

Be it known that I, WILLIAM J. LUTTON, a citizen of the United States, and a resident of Paterson, in the county of Passaic and State 5 of New Jersey, have invented a new and useful Improvement in Pattern Mechanism for Looms, of which the following is a specification.

My invention relates to an improvement in 10 looms, and has more particularly for its object to provide a new pattern-chain whereby the heddles may be operated to produce a great variety of weaves with a pattern-chain of very few bars, thus materially reducing the cost 15 of the pattern-chain and also the weight thereof.

A still further object is to provide a new pattern-chain in which rocking bars are provided with mutilated spools, so that when the 20 bars are turned in one direction the spools may be used to operate the heddles and when turned in the other direction will fail to operate the heddles.

A further object is to provide a loom in 25 which an indicator controlled by a box-chain is provided for turning the bars of the pattern-chain so as to call in the different weaves.

A practical embodiment of my invention is represented in the accompanying drawings, 30 in which—

Figure 1 is a transverse section through a loom embodying my invention. Fig. 2 is an enlarged detail side view of a portion of the loom, certain of the parts being broken away 35 to more clearly show the operation of my new pattern-chain. Fig. 3 is a detail sectional view showing the means for adjusting the indicator-bar. Fig. 4 is a detail view showing the means which I employ for preventing 40 the turning of the indicator-bar as it is reciprocated in the loom-frame. Fig. 5 is a detail view of the driving pattern-chain shaft, with its attached sprocket-wheels and guiding-wheel. Fig. 5^a is a similar view of the lower 45 idler-shaft, its sprocket-wheels, and guiding-wheel. Fig. 6 is a transverse vertical section through the pattern-chain and its support, showing the mutilated spools in different 50 positions and also showing several full spools. 55 Fig. 7 is a top plan view of a portion of the pattern-chain and its supports, showing the

spools in different positions. Fig. 8 is a transverse section through one of the pattern-chain bars, showing the single-spur tripper which is controlled by the indicator-roller. 55 Fig. 9 is a transverse section through the bar, showing the double-spur tripper operated by the permanent controlling-roller. Fig. 10 is a transverse section through the bar, showing one of the mutilated spools in its bottom 60 position. Fig. 11 is a similar view showing one of the mutilated spools in its top position. Fig. 12 is a similar view showing one of the full spools. Fig. 13 is a detail view, in top plane, of the support at one side of the pattern-chain; and Fig. 14 is a similar view of the support at the other side of the pattern-chain. 65

The loom-frame herein represented is denoted by 1. Two heddles 2 and 3, with their 70 operating mechanisms, are also represented.

The pattern-chain is composed of a series of angular bars 4, connected at their opposite ends by two series of links 5 and 6. In the present instance I have shown these bars 4 75 as being square in cross-section. The space between the two series of side links 5 and 6 upon each of the bars 4 is filled by a plurality of collars 7 of equal lengths. Some of these collars 7 are provided with full spools 8, 80 which will always raise one of the heddle-controlling bars when brought in contact therewith. Others of the collars 7 are provided with mutilated spools 9.

The collars 7, which have the mutilated 85 spools 9 thereon, are keyed to turn with the bar 4, preferably by providing the said sleeves with angular sockets corresponding to the shape in cross-section of the said bar.

On any one particular bar—such, for instance, as the upper bar shown in Fig. 6, which is the same bar as the lower bar shown in Fig. 7—two of the mutilated spools are placed upon the bar opposite to two others of the mutilated spools. This bar is also provided with a complete spool 8. It will thus be seen that when this bar is turned to one position one set of two of the mutilated spools 9 will be caused to engage the heddle-controlling bars, and when the said bar is turned into another position, a half revolution from the first-named position, the other two muti- 90 95 100

lated spools 9 will be brought into position to raise their corresponding heddle-controlling bars. Therefore whenever this particular bar is brought into position to operate the 5 heddles, the full spool 8 will always operate its heddle-controlling bar and two of the mutilated spools 9 will operate their corresponding heddle-controlling bars.

Each of the cross-bars 4 of the chain is provided near one end with a single-spur tripper, fitted to be engaged by the indicator-controlled roller when in its lower position. This single-spur tripper is constructed by providing a collar 10 of the same length as 10 the collars 7 and providing the said collar 10 with a spur 11. This tripper is fixed to rock with the bar 4, preferably by providing the socket therethrough to correspond with the shape in cross-section of the said bar. 15

Each of the bars 4 is provided at one end, preferably the end adjacent to the series of side links 6, with a double-spur tripper fixed to rock with the said bar. This double-spur tripper is made, preferably, by providing a 20 collar 12, having a socket therethrough corresponding to the shape in cross-section of the bar 4, which collar is provided with oppositely-extended spurs 13 and 14, arranged at right angles to the single spur 11 of the single-spur tripper. These double-spur trippers are fitted to be engaged by a controlling-roller carried by the frame, which will be hereinafter described. 25

The pattern-chain passes around an upper driving-shaft 15 and a lower idler-shaft 16, in engagement with the usual pairs of sprocket-wheels 17 and 18, which engage the series of side links 5 and 6.

The series of side links 5 and 6 of the pattern-chain rest upon rigid guides 19 and 20, secured to the frame as they pass from the sprocket-wheels 17 to the sprocket-wheels 18. The said series of side links 5 and 6 are also supported for a part of the distance as they 30 pass from the sprocket-wheels 18 to the sprocket-wheels 17 by guides 21 22, which are held in position by pairs of looped supporting-bars 23 24, which connect the guides 21 22 with the supports 19 and 20. The recesses through the side links are sufficiently large to permit the angular cross-bars 4 to freely rock therein. 45

The bars 4 are prevented from turning while passing around the driving-shaft 15 by 50 means of a guiding-wheel 25, which is in alinement with the double-spur trippers 13 and 14. The mutilated spools 9 upon each bar as it passes beneath the heddle-controlling bar will therefore be held in its proper positions 55 to raise the bars to pass idly beneath the same. The bars 4 are also held from turning while passing around the idler-shaft 16 by means of a similar guiding-wheel 26, also in alinement with the double-spur trippers 60 65 13 and 14.

The means which I employ for rocking the bars a half-revolution in one direction by two successive movements and a half-revolution back by two successive revolutions, when so desired, is constructed and arranged as follows: A box-chain 27 is provided at suitable intervals with spools 28, which box-chain passes around a sprocket-wheel 29 on the upper driving-shaft 15 of the pattern-chain. 70

A rock-bar 30, similar to the heddle-controlled bars, is mounted in position to be engaged and raised by the spools 28 of the box-chain, the said rock-bar 30 being fitted to raise and lower an indicator-roller 31 out of and into the path of the single-spur trippers 8c 11. This rock-bar 30 is connected to the roller 31 as follows: The roller 31 is carried by the lower end of a vertically-reciprocating rod 32, the upper end of which is adjustably secured to one arm, 33, of a rocking lever 85 pivoted to the frame at 34, the other arm, 35, of the said lever being connected to the free end of the rock-bar 30 through a link 36. 90

The vertically-reciprocating rod 32 passes through a horizontal rail 37 of the frame and is prevented from turning therein preferably by squaring the rod 32 where it passes through the rail 37, as shown at 38.

The double-spur-tripper-controlling roller 39 is mounted in the free end of an arm 40, 95 supported by the rail 37, so that the said roller 39 is located in the path of the double-spur trippers.

Two fingers 41 42 are secured to the guide 21, the finger 41 being extended into the path 100 of the single-spur tripper 11 and the finger 42 being extended into the path of the double-spur tripper 13 14.

An intermediate guide-finger 43 is arranged to hold the chain down against its 105 support 19 while the bar is being turned by the preceding single-spur tripper because of its engagement with the finger 41.

The pattern-chain is placed in position around the shafts 15 and 16 with the single-spur trippers projecting outwardly from the chain. When the bars of the chain are in this position, with the single-spur trippers projecting outwardly, the double-spur trippers will be located longitudinally of the chain 115 and a certain series of mutilated spools will be in position to raise their corresponding heddle-controlling bars, while the other series of mutilated spools will be in position to pass freely under their corresponding heddle-controlling bars, without operating the same. As the bars of the chain leave the sprocket-wheels 18 on the shaft 16 the single-spur trippers 11 project outwardly. 120

If it is desired to turn a bar a half-revolution to turn certain of its mutilated spools out of position to engage their heddle-controlling bars and the other mutilated spools into position to engage their heddle-controlling bars, it is done as follows: One of the 130

spools 28 upon the box-chain 27 is brought into engagement with the rock-bar 30 in time to lower the single-spur-tripper-controlling roller 31 into the path of the single-spur tripper carried by the bar which it is intended to turn. As the pattern-chain is moved along by the driving-shaft 15 and its sprocket-wheels 17 the roller will turn the bar 4 a quarter-revolution, thus bringing the double-spur tripper 13 14 into a position at right angles to the chain. As the chain continues to move forwardly the controlling-roller 39 will engage the spur of the double-spur tripper which projects outwardly and turn the bar 4 another quarter-revolution. This will bring the mutilated spools which were projecting outwardly into a position projecting inwardly and also bring the mutilated spools which were projecting inwardly into a position projecting outwardly from the chain. The bar passes around the driving-shaft 15 beneath the heddle-controlling bars in this position. When the box-chain 27 fails to lower the controlling-roller 31 into the path of the single-spur trippers 11, the bars will travel along up to the heddle-controlling bars without being shifted, for the reason that the controlling-roller 39 will pass along the outer sides of the double-spur trippers 13 14 without turning the same, as the said double-spur trippers will be arranged longitudinally of the chain. The bars are always returned to their normal position before they reach the shaft 16 by the following mechanism: As the pattern-chain leaves the shaft 15 the finger 41 will engage any inwardly-projected single-spur trippers 11, and thus turn the bar 4 backwardly a quarter-revolution. While this is being done the pressure of the guide-finger 43 holds the chain firmly down upon its support 19. Before the chain reaches the shaft 16 the finger 42 will engage any inwardly-projecting spur of the double-spur trippers 13 14, thus turning the bars 4 a quarter-revolution back to their normal position.

By the arrangement hereinabove described it will be seen that I am enabled to produce a great many changes in the weave with a very short chain, for the reason that the changes in the pattern can be controlled from the box-chain so as to produce a great number of combinations in the mutilated spools.

In the device herein shown the loom will be weaving the ground-weave when the single-spur trippers are projecting outwardly and the cross-stripe weave may be called in at any time from the box-chain by lowering the roller 31 into position to engage one of the outwardly-projected single-spur trippers for bringing the double-spur tripper into position to be engaged by the roller 39 for completing a half-revolution of the pattern-chain bar, as has been heretofore clearly described.

What I claim is—

65 1. In a loom, a pattern-chain, mutilated

spools carried thereby, and means for bringing a spool into and another spool out of operative position.

2. In a loom, a pattern-chain, mutilated spools carried thereby, a box-chain and means under the control of the box-chain for bringing a mutilated spool into an operative position and another mutilated spool out of operative position. 7c

3. In a loom, a pattern-chain, mutilated spools and spur-trippers carried by the chain and means for engaging the trippers for bringing a mutilated spool into operative position and another mutilated spool out of operative position. 75 80

4. In a loom, a pattern-chain, mutilated spools carried thereby, an indicator-roller and means for operating it for bringing a spool partially into and another spool partially out of operative position and a controlling-roller arranged to complete the movement to bring a spool into operative position and another spool out of operative position. 85

5. In a loom, a pattern-chain, mutilated spools carried thereby, two series of spur-trippers carried by the chain, an indicator-roller fitted to be brought into and out of engagement with one series of spur-trippers and a stationary roller located in position to engage the other series of spur-trippers for bringing a mutilated spool into and another mutilated spool out of operative position. 90 95

6. In a loom, a pattern-chain, mutilated spools carried thereby, means for bringing a mutilated spool into and another spool out of operative position and separate means for returning the spools to their original position. 100

7. In a loom, a pattern-chain, a driving-shaft therefor, mutilated spools carried by the chain, means for turning the spools out of their normal position before reaching the said driving-shaft and means for returning the spools to their normal position after leaving the driving-shaft. 105

8. In a loom, a pattern-chain, a driving-shaft therefor, mutilated spools and spur-trippers carried by the chain, means for engaging the trippers for turning the spools out of their normal position before reaching the driving-shaft and means for engaging the trippers for returning the spools to their normal position after leaving the driving-shaft. 110 115

9. In a loom, a pattern-chain, a driving-shaft therefor, mutilated spools and spur-trippers carried by the chain, means engaging the trippers for turning the spools out of their normal position before reaching the driving-shaft and means for returning the spools to their normal position after leaving the driving-shaft comprising fingers arranged to engage the said spur-trippers. 120 125

10. In a loom, a pattern-chain, a driving-shaft therefor, mutilated spools, and two series of spur-trippers carried by the chain-controlling rollers for each series of spur-trippers 130

for turning the mutilated spools out of their normal position before reaching the driving-shaft and an engaging-finger for each series of spur-trippers for returning the mutilated 5 spools to their normal position after leaving the said driving-shaft.

In testimony that I claim the foregoing as

my invention I have signed my name, in presence of two witnesses, this 7th day of October, 1902.

WILLIAM J. LUTTON.
